UNITED STATES PATENT OFFICE.

SILAS B. BROWN, OF CINCINNATI, OHIO, ASSIGNOR TO THE EDWARDS MANUFACTURING COMPANY, OF CINCINNATI, OHIO, A CORPORATION OF OHIO.

TOY PISTOL.

1,250,425.

Specification of Letters Patent. Patented Dec. 18, 1917.

Application filed May 8, 1917. Serial No. 167,328.

To all whom it may concern:

Be it known that I, SILAS B. BROWN, a citizen of the United States, and residing at Cincinnati, in the county of Hamilton and State of Ohio, have invented a new and useful Improvement in Toy Pistols, of which the following specification is a full disclosure.

My invention relates to detonating devices and more particularly to that type designed in simulation of an automatic pistol wherein a percussion cap tape is acted upon by feeding or firing mechanism.

An object of the invention is to provide a supporting frame and firing elements of cast metal, requiring no machining, the parts being designed to provide coöperating guide surfaces insuring a true and accurate operation.

Another object is to provide a supporting frame and firing mechanism with means for deflecting the fire of an exploded cap to prevent a premature ignition of an unexploded cap.

Another object is to provide a box-like skeleton frame and coöperating firing elements urged transversely against each other and against the inner side wall guiding surface of the frame and normalized by double functioned spring members.

The features of the invention will be more fully set forth in the description of the accompanying drawings forming a part of this specification, wherein:

Figure 1 is a left side elevation showing the open casing in dotted lines.

Fig. 2 is a right side elevation, partly in section to more clearly show the operating parts.

Fig. 3 is a view similar to Fig. 2, showing the parts in partly operated position.

Fig. 4 is a plan section on line 4—4 of Fig. 3.

Fig. 5 is a perspective view of the frame casting looking from the right hand side.

Fig. 6 is a perspective view of the trigger member.

Fig. 7 is a perspective view of the hammer member.

The mechanism illustrated in the drawings is adapted to be supported in a hinged two-part casing in simulation of an automatic pistol, but the scope of the invention obviously includes various other types of casing and specific forms of mechanism,

compatible with the broad principles herein claimed.

The entire mechanism is assembled in the box-like skeleton frame A, as a unitary structure, and is subsequently secured within the casing section B by a series of ears 1, projecting from the edges thereof and bent over the marginal edges of said frame. The casing cover section C is hinged to the section B, both sections being provided with a muzzle opening D affording an exit for the cap tape.

The frame is comprised of three side plates 10, 11, 12, forming the right hand side thereof, a bottom rail 13 and two side tie-bars 14, 15, forming the left hand side and a top shelf or anvil plate 16, all connected by transverse webs to form an integral support for the operating mechanism.

Two pivot studs 17, 18 project inwardly from the side plate 11 and a supply ammunition roll stud 19 projects inwardly from the side plate 10. The ammunition is a standard type of paper web 20 having longitudinally spaced percussion caps and is fed along the under side of the anvil plate 16 from the supply roll positioned upon the stud 19. A leaf spring 21 is retained in position by a projection 22 as an extension of the side plate 11 and by transverse projections 23, 24 extending from the plate 10 and tie-bar 14 and by the web 25 connecting the plates 10 and 11. Said spring extends upwardly and forwardly, its upper end engaging the ammunition tape in rear of a percussion cap, (when the mechanism is in normal position), to prevent retrograde movement of said tape.

The trigger member 30 pivoted on the stud 17 consists of a finger piece 31 having an inclined trip projection 32, an upper feed pawl operating end 33, having a pawl pivot seat 34, and a hammer member guide finger 35. The feed pawl 36 has a bifurcated lower end seating against the pivot seat 34, the 100 furcations 37, 38 extending over either side of said seat to retain the pawl against lateral displacement. The upper feed end of the pawl 36 rests against the under side of the tape 20 and engages each successive percussion cap during successive feed strokes to feed the tape forwardly toward the hammer.

A coil spring 40 surrounds the trigger stud 17 intermediate of the trigger member 11.

30 and the side plate 11, and exerts a transverse tension against the inner side of said trigger member forcing it outwardly so that the outer surface of the finger piece 31 is 5 forcibly held in contact with the inner surface of the bottom rail 13 between the webs 41, 42 and the outer surface of the pawl operating end 33 against the inner surface of the tie-bar 14. This provides a pivoted trigger member having two guiding contact surfaces and as the inner surfaces of the bottom rail 13 and tie-bar 14 are in the same vertical plane the action of said trigger member is true and accurate. The spring also 10 has a circular tension which acts on the feed pawl in the following manner.

The one end 43 engages a projection 44 extending inwardly from the side plate 11 and the other end 45 engages through an 20 aperture 46 in the feed pawl 36, said pawl being slightly angled at this point to bring the point of spring contact beyond the dead center line of the feed and pivot ends of the pawl so that the circular tension of the 25 spring tends to hold the feed end of the pawl in operating contact with the ammunition tape.

The hammer member 55 is formed with a hammer head 50, a trip finger 51, and an 20 alining finger 52, and is pivoted on the stud 18. A coil spring 53 surrounds the hammer stud 18 intermediate of said hammer member and the side plate 11 and exerts a transverse tension against the inner side thereof, 35 forcing it outwardly so that the side of the hammer head 50 is held in contact with the inner surface of the tie-bar 15, the inner surface of the trip finger in contact with the inner surface of the finger piece 31 and its 40 inclined trip projection 32 and the alining finger 52 in contact with the inner surface of the pawl operating end 33 of the trigger member 36. This provides a three-point alining contact for the hammer member insuring its true and accurate operation.

One end of the spring 53 engages a projection on the web 42 and the opposite end engages a projection 54 on the head end of the hammer member 55, the circular tension 50 of said spring tending to return the hammer head forcibly against the anvil plate to explode the percussion caps.

As the trigger member is operated the inclined trip projection 32 acting against the trip finger 51 of the hammer member 55, rocks said hammer member and by reason of the relative dispositions of the two pivot studs 17, 18, the inclined trip projection 32 will travel downwardly and away from the lower point of the trip finger 51 (see Fig. 3) until it disengages said projection 32 and releases the hammer member. On the return stroke of the trigger member the trip finger 51 wipes over the inner surface of the guide finger 35 and the inclined trip projection 32

of the trigger member to its normal position in the rear of said projection, there being sufficient free play between the hammer member and its pivot stud to permit this movement.

The hammer head 50 and the anvil plate 16 adjacent to said hammer head are formed to provide means for confining and directing the fire of the exploded cap so that a premature ignition of one or more adjacent caps is prevented and the fire of the exploded cap is directed toward the muzzle opening of the casing.

It will be noted that the under side of the anvil plate 16 is provided with an inclined rib 60 immediately in rear of the point of hammer contact and that the heel of the hammer head 50 is sharply inclined rearwardly and downwardly. This construction constitutes a means for directing any fire which should escape rearwardly past the striking crown 61 of the hammer head, downwardly away from the next succeeding cap 62 which normally is positioned directly in the rear of the protecting rib 60. From the striking crown 61, forwardly, the hammer head surface is inclined forwardly and downwardly and the anvil plate has a second rib 63 inclined forwardly and downwardly at a lesser angle than the hammer head surface and forming therewith, (when the hammer head is in normal position), a diverging fire directing throat 64 for directing the fire of the exploded cap and the exploded cap tape toward the muzzle opening or exit D.

Adjacent to the fire zone, the anvil plate 16 is provided with a fire shield 65 formed by a downward extension of said plate. This is a safety element serving to direct the fire downwardly thereby guarding against accidents resulting from a firing of the pistol with the casing cover open.

The pawl end 33 of the trigger member 30 is provided with an elongated aperture 70 as a continuation of the pivot aperture. This is an assembling slot and has no function in the operation of the device.

The above described mechanism provides a device comprised of cast metal parts requiring no machining and in which the operating parts are guided throughout their movements to insure a true and accurate co-operation. This provides a cheap and effective device not liable to disarrangement by rough usage or by slight variations in the sizes or forms of the parts.

Having described my invention, I claim:

1. A device of the class described adapted for inclosure in a pistol shell, and comprising a unitary, box-like skeleton frame adapted for operatively supporting the firing elements internally of the frame and enabling the convenient assembly of said elements between the members constituting this skeleton frame.

2. A device of the class described adapted for inclosure in a pistol shell, and comprising a unitary, box-like skeleton frame adapted for operatively supporting the firing elements internally of the frame, the trigger having a fulcrum within the frame and bearings for its opposite moving ends on portions of the frame, and a tension element for normalizing the trigger and holding it in 10 said bearing relation to the frame.
3. A device of the class described adapted for inclosure in a pistol shell, and comprising a unitary, box-like skeleton frame adapted for operatively supporting the firing elements internally of the frame, the trigger having a fulcrum within the frame and bearings for its opposite moving ends on portions of the frame, a tension element for normalizing the trigger and holding it in 15 said bearing relation to the frame, a hammer member having an intermediate fulcrum in the frame and having bearings against the trigger element and the frame, and adapted to be operated by the trigger, 20 and a tension element for normalizing the hammer.
4. A device of the class described adapted for inclosure in a pistol shell, and comprising a unitary, box-like skeleton frame adapted for operatively supporting internally of the frame a trigger, hammer and ammunition tape feed, the upper portion of the frame constituting a firing anvil coacting with the hammer over which the tape passes, 30 said frame in the rear of the anvil being formed to prevent back firing, and the forward end of the anvil and hammer forming a throat directing the fire to the muzzle.
5. A device of the class described adapted 40 for inclosure in a pistol shell, and comprising a unitary, box-like skeleton frame, having top and bottom and opposite side members, adapted for conveniently assembling
- the firing elements within the frame, the firing elements being fulcrumed upon one side member of the frame and having an outward bearing on the opposite side member of the frame, and tension means for normalizing the firing elements and holding them movably against the frame bearings. 45
6. A device of the class described adapted for inclosure in a pistol shell, and comprising a unitary, box-like skeleton frame adapted for operatively supporting the firing elements internally of the frame and enabling 50 convenient assembly of said elements between the frame members, the firing elements comprising trigger and hammer members fulcrumed within the frame and adapted for coaction, said trigger and hammer elements having bearings upon the frame and upon one another, and a portion of the frame constituting the firing anvil for the hammer. 55
7. A device of the class described, comprising a frame, having vertical guide surfaces and an anvil plate, a trigger member pivoted on said frame, means exerting a transverse tension yieldingly retaining said member in contact with the guide surfaces 60 and a circular tension normalizing the trigger member, a hammer member coöperating with the anvil plate and pivoted on the frame, and a second means exerting a transverse tension yieldingly retaining the hammer member in coöperative engagement with the trigger member and in contact with a guide surface of the frame and a circular tension normalizing the hammer member. 65
- In witness whereof, I hereunto subscribe 70 my name, as attested by the two subscribing witnesses.
